UNITED STATES PATENT OFFICE.

CHARLES L. INGALLS, OF LOWELL, MASSACHUSETTS, ASSIGNOR OF ONE-HALF TO OTHELLO P. DAVIS, OF SAME PLACE.

DESIGN FOR A DRINKING-CUP.

SPECIFICATION forming part of Design No. 23,682, dated October 9, 1894.

Application filed July 30, 1894. Serial No. 519,034. Term of patent 14 years.

To all whom it may concern:

Be it known that I, CHARLES L. INGALLS, of Lowell, in the county of Middlesex and State of Massachusetts, have invented a certain new and original Design for a Drinking Vessel, of which the following is a specification.

Reference is to be had to the accompanying drawings, of which—

Figure 1 is a perspective view of a drinking vessel showing my design. Fig. 2 is a central vertical sectional view thereof taken on the line 2—2 of Fig. 1. Fig. 3 is a sectional view taken on the line 3—3 of Fig. 2. Fig. 4 is a sectional view taken on the line 4—4 of Fig. 1.

The several views are deemed necessary to fully illustrate my design.

The leading feature of my invention is the symmetrical undulating transverse curvature (simulating that of a "Cupid's bow") of the lip-guard, as viewed from above, and the upward flare or rise of the central inner edge of the said lip-guard.

In the drawings—*a* is the body of the drinking vessel and *b* is the guard for the upper

lip or mustache. The upper surface of the guard *b* if made symmetrically undulating in form as is shown in the drawings; that is, from each side of the glass along the line where the guard *b* connects therewith the upper surface rises gradually for a short distance and then curves over and downward toward the center, meeting at the center without the angle, so as to form substantially a line simulating in form a Cupid's bow, as is best represented in Fig. 4. The inner edge of the guard *b* at its center is flared or rises upwardly as at *c*, as is best represented in Fig. 3.

What I claim is—

The design for a drinking vessel as herein shown and described.

In testimony whereof I have signed my name to this specification, in the presence of two subscribing witnesses, this 18th day of July, A. D. 1894.

CHARLES L. INGALLS.

Witnesses:

ARTHUR W. CROSSLEY,
C. C. STECHER.
